UNITED STATES PATENT OFFICE

2,528,858

SMOKING PIPE

Frank P. Catalano, Joseph P. Catalano, and Peter P. Catalano, North Collins, N. Y., assignors to Panepinto Mfg. Corp., North Collins, N. Y., a corporation of New York

Application October 13, 1947, Serial No. 779,506

1 Claim. (Cl. 131—184)

1 This invention relates to smoking pipes.

An object of this invention is to provide an improved smoking pipe which is so constructed as to provide a dry tobacco bowl so that substantially all of the tobacco in the bowl may be used.

Another object of this invention is to provide a smoking pipe wherein the mouthpiece has secured thereto a cleaning plunger which upon removal of the mouthpiece will clean the bore of the stem.

Another object of this invention is to provide in a smoking pipe an improved means for preventing the passage of saliva from the mouthpiece into the stem so that the tobacco in the lower portion of the bowl will not become moistened.

A further object of this invention is to provide a smoking pipe which includes an improved biting element formed with the mouthpiece so as to prevent collapse of the mouthpiece at the point where it is engaged in the mouth of the smoker.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a longitudinal section of a smoking pipe constructed according to an embodiment of this invention, portions of the rod assembly being shown in elevation.

Figure 2 is a plan view of the rod assembly.

Figure 3 is a detailed side elevation of the rod assembly, partly broken away and in section.

Figure 4 is a sectional view taken on the line 4—4 of Figure 1.

Referring to the drawing, the numeral 10 designates generally the bowl of a smoking pipe which has extending therefrom a stem 11. The stem 11 is formed with a lengthwise extending bore 12 and a passage 13 extends from the forward end of the bore 12 and communicates with the interior of the bowl 10 at a point forwardly of the center of the bowl 10. A mouthpiece 14 is engaged with the stem 11 being provided with an internally threaded stud 15 frictionally engaging within the inner or rear end of the bore 12. The mouthpiece 14 is provided with a lengthwise extending bore 16 and, in the present instance, the mouthpiece 14 includes an inner biting portion 17 which is integral with the mouthpiece member 14. The inner biting portion 17 is reinforced by a sleeve

2 or tubular member 18 which may be made of metal or the like.

An elongated plunger rod, rod assembly generally indicated at 26, includes a shank portion 19 and is threaded at its mid point 20 into the stud 15. Portion 19 extends lengthwise of the bore 12 of the stem 11. The portion 19 has at the forward end thereof a piston or head 21 which is of a diameter slightly less than the diameter of the bore 12 so that the head 21 can be readily pulled through the bore 12 upon removal of the mouthpiece 14.

The plunger rod assembly 26 also includes a small integral coaxial rod 22 of lesser diameter than portion 19, which comprises a second shank which terminates in an inner head 23. The intermediate threaded portion of the plunger rod 26 is formed with an elongated arcuate groove 24 providing communication between the bore 12 and the bore 16. The inner end of the rod 22 and the head 23 are also formed with a slot 25 so that the smoke may freely be drawn past the head 23.

The rod 22 forms with the inner end of the plunger rod 19 a moisture trap which will tend to prevent any saliva from flowing outwardly from the bore 16 into the bore 12 of the stem.

In the use of this smoking pipe the bowl 10 is filled in the normal manner and the smoke drawn through the bore 12 of the stem 11 and through the bore 16 of the mouthpiece 14. When it is desired to clean the stem 11, the mouthpiece 14 is removed from the stem 11 drawing therewith the plunger rod 19 and the plunger member or head 21. As the plunger 21 is drawn through the bore 12 accumulations within the bore 12 will be drawn therewith.

The head 23 also constitutes a cleaning member for removing accumulations within the bore 16. The bore 16 is cleaned by unthreading rod 19 from stud 15 and pulling rod 22 and head outwardly of bore 16.

What is claimed is:

In a smoking pipe, a stem with a bore therethrough and a mouthpiece having a bore of lesser diameter than said first bore, a reduced stud connecting said mouthpiece and said stem, said stud being internally threaded, a plunger rod assembly including a threaded intermediate portion and oppositely extending shank portions of different diameters extending into said bores, said threaded intermediate portion engaging the internal threads of said second bore whereby said stud constitutes the sole support of said shanks in said bores, a smoke passage extending through

said threaded intermediate portion, and a head at the extremity of each shank portion adapted to fit into the bore in which it is positioned, whereby upon withdrawal each head may clean its associated bore.
